(57) **CLAIM**

I claim the ornamental design for a coffee brewing system, as shown and described.

DESCRIPTION

FIG. 1 is an upper front perspective view of a coffee brewing system in accordance with the present invention;

FIG. 2 is an upper rear perspective view thereof;

FIG. 3 is a lower rear perspective view thereof;

FIG. 4 is a lower front perspective view thereof;

FIG. 5 is a left view thereof;

FIG. 6 is a right view thereof;

FIG. 7 is a front view thereof;

FIG. 8 is a rear view thereof;

FIG. 9 is a top view thereof; and

FIG. 10 is a bottom view thereof.

FIG. 11 is a second embodiment of a coffee brewing system shown in an upper front perspective view.

FIG. 12 is an upper rear perspective view thereof;

FIG. 13 is a lower rear perspective view thereof;

FIG. 14 is a lower front perspective view thereof;

FIG. 15 is a left view thereof;

FIG. 16 is a right view thereof;

FIG. 17 is a front view thereof;

FIG. 18 is a rear view thereof;

FIG. 19 is a top view thereof; and,

FIG. 20 is a bottom view thereof.
